T. D. McCARTY.

RAILROAD TIE.

APPLICATION FILED OCT. 27, 1920.

1,425,783.

Patented Aug. 15, 1922.

Inventor —

Thomas D. McCarty
by Cook & McCarty, Atty.

UNITED STATES PATENT OFFICE.

THOMAS D. McCARTY, OF HAWK POINT, MISSOURI.

RAILROAD TIE.

1,425,783.

Specification of Letters Patent. Patented Aug. 15, 1922.

Application filed October 27, 1920. Serial No. 419,800.

To all whom it may concern:

Be it known that I, THOMAS D. McCARTY, a citizen of the United States of America, a resident of Hawk Point, in the county of Lincoln and State of Missouri, have invented 5 certain new and useful Improvements in Railroad Ties, of which the following is a full, clear, and exact description, reference being had to the accompanying drawings, 10 forming a part of this specification.

This invention relates to improvements in railroad ties, one of the objects being to produce a strong and simple railroad tie comprising a concrete body provided with resilient rail supporting members, preferably 15 wooden blocks. A further object is to provide a simple means for reinforcing the concrete body, in combination with rail fastening means whereby the rails and wooden 20 blocks may be securely attached to the reinforcing means in the concrete.

Fig. I is a top or plan view of a railroad tie embodying the features of this invention.

Fig. II is an enlarged longitudinal section 25 of the elements shown in Fig. I, the middle portion of the tie being broken away.

Fig. III is a transverse section taken approximately on the line III—III, Fig. II.

As an illustration of one form of the 30 invention, I have shown a railroad tie comprising a concrete body A provided with recesses in its top face, and resilient blocks B seated in said recesses, said resilient blocks being preferably made of wood. The blocks 35 and recesses may be equal in width to the concrete body A, and in this event the concrete will be comparatively weak at points directly below the rails 1 which rest upon the blocks B.

40 To reinforce the concrete structure, a pair of longitudinal reinforcing bars 2 is located in the concrete body, and these bars extend from one end of said body to the other end thereof. In the structure I have shown, 45 the top faces of the flat reinforcing bars 2 are flush with the bottom walls of the recesses in which the resilient blocks B are mounted, and these blocks are seated upon the reinforcing bars as well as upon the concrete forming the bottom walls of the recesses.

The rail fasteners herein shown include 50 vertical bolts 3 extending through the reinforcing bars, and also through the resilient blocks B, each of said bolts having a head 3' anchored in the concrete below one of the

reinforcing bars and a threaded upper end 60 projecting from the top of one of the resilient blocks. 4 designates rail fastening clips mounted on the extended upper ends of bolts 3 and overlapping the rails, as shown in the drawings. To secure the clips 4, nuts 5 are 65 screwed onto the upper ends of bolts 3. It will be observed that each resilient block B is provided with a pair of the attaching 70 bolts 3 and that one of the bolts of this pair is secured to one of the reinforcing bars 2, while the other bolt is secured to the other reinforcing bar.

The bolt heads 3' are anchored in the concrete 75 in such a manner that they serve as means for anchoring the reinforcing bars 2. The vertical bolts 3 also perform the added functions of securing the resilient blocks B to the concrete and at the same time serving 80 as means for connecting the rail fastening members 4 to the reinforcing bars 2 in the concrete. The simple reinforcing bars 2 are therefore firmly anchored in the concrete and the rails are securely attached to the reinforcing bars through the medium of the bolts 3, which also serve as means for attaching 85 the resilient blocks to the tie.

I claim:

A railroad tie comprising a concrete body 85 provided with recesses in its top face, resilient blocks in said recesses, said recesses and resilient blocks being equal in width to said concrete body, a pair of longitudinal reinforcing bars located in said concrete body 90 and extending from one end of said body to the other end thereof, the top faces of said reinforcing bars being flush with the bottom walls of said recesses to form seats for said resilient blocks, and pairs of rail fasteners 95 including pairs of vertical bolts extending through said reinforcing bars and also through the resilient blocks, one bolt of each of said pairs of bolts extending through one of said longitudinal reinforcing bars, and 100 the other bolt of each pair of bolts extending through the other of said reinforcing bars, each of said vertical bolts having a head anchored in the concrete directly below the reinforcing bar and a threaded upper end projecting from the top of one of said resilient blocks, and threaded nuts screwed onto the threaded upper ends of said bolts.

105 In testimony that I claim the foregoing I hereunto affix my signature.

THOMAS D. McCARTY.
